UNITED STATES PATENT OFFICE.

GALES P. MOORE, OF ST. LOUIS, MISSOURI, ASSIGNOR TO THE CONTROLLER COMPANY OF AMERICA, OF ST. LOUIS, MISSOURI, A CORPORATION OF MISSOURI.

TELEPHONE-LOCK.

SPECIFICATION forming part of Letters Patent No. 712,950, dated November 4, 1902.

Application filed June 4, 1902. Serial No. 110,174. (No model.)

To all whom it may concern:

Be it known that I, GALES P. MOORE, a citizen of the United States, residing at St. Louis, Missouri, have invented a certain new and useful Improvement in Telephone-Locks, of which the following is a full, clear, and exact description, such as will enable others skilled in the art to which it appertains to make and use the same, reference being had to the accompanying drawings, forming part of this specification, in which—

Figure 1 is a front elevation of a portion of a telephone-box with my invention applied. Fig. 2 is a side elevation, partly in section, illustrating the locking mechanism in locking position. Fig. 3 is a top plan view partly in section. Fig. 4 is a view, partly in section, showing the moving parts in the position assumed upon the introduction of a coin. Fig. 5 is a view of the character of Fig. 4, showing the positions assumed by said moving parts as the suspension-hook rises and the coin is being discharged. Fig. 6 is a view of the character of Fig. 4, showing the positions assumed by the said moving parts when the suspension-hook is fully elevated and after the locking-lever has recovered from the action of the coin thereon; and Fig. 7 is a view illustrating a modification.

My invention relates to telephone-locks, and more particularly to locks of such character operated by coins or the like, my object being to provide a simple and efficient mechanism in which the member engaging the suspension-hook is a vertical slide, whereby the pivoting of such member is obviated and said member operates with a simple sliding action.

To this end and also to improve generally upon apparatus of the character indicated, my invention consists in the various matters hereinafter described and claimed.

Referring now more particularly to the drawings, 1 represents a telephone-box, which can be of any suitable construction, and 2 indicates the customary suspension-hook for the usual telephone-receiver 3. A box or casing 4 is secured to the wall or other suitable support to extend at the side of the said telephone-box and over the said suspension-hook, said casing containing the hereinafter-described locking mechanism and being provided with

a coin-slot 5 and raceway 6 and also with a horizontal slot 7 in one of its horizontal walls, (preferably the bottom wall,) suitable guides 8 preferably extending from said slot 7. A 55 substantially vertical slide-bar 9 extends through said casing-slot 7 and between said guides and rests above and upon the suspension-hook, said slide-bar being preferably provided with a slot through which a guide-pin 10 extends. Near its upper end the said bar is provided with a locking part 11, which is preferably a surface inclining inwardly and downwardly from the edge adjacent the herein-after-mentioned locking-lever, and from 65 the inner end of said locking-surface the said bar has a part which extends upwardly and laterally over the end of the herein-after-mentioned locking-arm and then downwardly to produce an overhanging projection or stop 12. 70 A bell-crank locking-lever 13 is pivoted intermediate the coin-raceway and the said slide-bar, the coin-receiving arm 14 of said lever extending from the pivot to a point under the said raceway, while the locking-arm 75 15 of said lever has a hook 16 upon its upper end, said hook co-operating with the before-mentioned locking-surface of the slide-bar. For a purpose to be herein-after explained the arms of the said locking-lever are of such 80 relative weights that the arm 15 overbalances the arm 14, and the pivot of the said lever is at such a point that the lever can be rocked to carry the hook 16 out of engagement with the slide-bar and also to deposit the operating coin or token without moving the said arm 15 beyond the center of gravity. If desired, a stop-pin 17 can be provided in rear of said arm 15 in order to prevent the same being thrown beyond the vertical line, including 90 the said pivot, as said arm is moved backwardly.

Normally the slide-bar rests upon the suspension-hook and the locking-lever lies with its coin-receiving arm in elevated position 95 under the coin-raceway and its hook engaging the locking-surface of the slide-bar and intermediate the body of the said bar and the overhanging projection, all as shown in Fig. 2. The suspension-hook is thus locked 100 against movement, and as this hook controls the circuit through the telephone in a well-

known manner the telephone cannot be used. When a coin or token is deposited in the race-way, it falls upon the end of arm 14 and tilts the locking-lever until the hook 16 disengages 5 the locking-surface 11 and the upper end of arm 15 engages the overhanging projection, as shown in Fig. 4, the parts being so proportioned and arranged that when the said lever is in this position its arm 14 still supports the coin or 10 token, whereby the lever is maintained in the position last described. When the receiver is lifted from the suspension-hook, the usual spring elevates said hook in a well-known manner, and as said hook rises it carries the 15 slide-bar with it, thus moving the said overhanging projection out of engagement with the locking-lever and permitting the coin to rock the said lever sufficiently to cause said coin to be deposited therefrom, as 20 shown in Fig. 5. By the time that the coin has fallen from the coin-receiving arm 14 the slide-bar has been so elevated that its locking-surface is above the point it occupies when engaged by the hook of the locking-lever, and therefore when the coin leaves the 25 arm 14 the overbalanced locking-lever rocks toward the slide-bar and the hook comes to rest against the edge of the same, as illustrated in Fig. 6. When the receiver is again 30 hung upon the suspension-hook, said hook is depressed, and the support for the slide-bar being thus lowered said bar falls into normal locking position, the locking-lever hook falling into locking position as soon as the locking-surface of the bar falls below the end of 35 said hook.

It will be noticed that the end of the arm 14 of the locking-lever normally lies under and near the lower end of the coin-raceway. 40 By reason of this fact the guiding-pin 10 can be dispensed with, if so desired, and the bar will still be retained in the casing and prevented from unduly protruding therefrom even when the casing is not in position and 45 the slide-bar is not supported upon the suspension-hook, for should the slide-bar fall its part over the locking-arm 15 engages said arm and the lever is merely rocked until its arm 14 engages the end of the coin-raceway. 50 The present mechanism is efficient and extremely simple in its construction and operation. Pivoting of the bar which engages the suspension-hook is avoided, danger of rusting or breaking of the pivot is removed, and the 55 bar acts directly upon the suspension-lever, merely sliding down upon the same by its own weight. The bar can be readily inserted through the casing-slot.

Manifestly the form of the locking-lever 60 need not be that shown in Fig. 2 of the drawings. It can, for example, be made as illustrated in Fig. 7, the lever shown in said latter-mentioned figure having a substantially vertical locking-arm 15^a, which lies along and 65 engages the edge of the slide-bar, and a sub-

stantially horizontal coin-receiving arm 14^a, the pivotal point 14^a of the lever being in said arm 14^a a suitable distance from the arm 15^a. Furthermore, the slide-bar can, as shown in Fig. 7, protrude through a slot in the top of 70 the casing and be provided with a hook 18, which engages over the suspension-hook. If necessary or desired, the slide-bar can be bent to bring the same in proper relation to the suspension-hook.

I am aware that many minor changes in the construction, arrangement, and combination of the several parts of my device can be made and substituted for those herein shown and described without in the least departing 80 from the nature and principle of my invention.

Having thus described my invention, what I claim as new, and desire to secure by Letters Patent, is—

1. In a telephone-lock or the like, a substantially vertically-slidable bar, a locking part thereon, a part upon said bar extending upwardly and laterally and then downwardly to produce an overhanging projection, and a 90 locking-lever having its end intermediate said locking part and overhanging projection and co-operating with said locking part, said overhanging projection being in the path of movement of said lever to limit its movement from 95 locking position; substantially as described.

2. In a telephone-lock or the like, a substantially vertically-slidable bar, guides therefor, a coin-raceway, a lever intermediate said bar and raceway, a locking-surface upon said bar above the pivotal point of said lever and inclining downwardly and away from said lever, a portion of said bar extending upwardly and laterally and then downwardly to produce an overhanging projection, a locking-arm in 105 said lever, a hook upon said locking-arm engaging said locking-surface and intermediate the body of said bar and said overhanging projection, said overhanging projection being in the path of movement of said lever to limit 110 its movement from locking position, and a coin-receiving arm in said lever extending below said raceway, said locking-arm overbalancing said coin-receiving arm, the pivotal point of said lever being such that it can be 115 rocked to deposit a coin without throwing said locking-arm backwardly beyond the center of gravity, and said bar having a surface engaged by said hook when the coin has been deposited and the bar elevated, said surface 120 sliding along said hook as the bar descends; substantially as described.

In testimony whereof I hereunto affix my signature, in the presence of two witnesses, this 2d day of June, 1902.

GALES P. MOORE.
